(57) CLAIM

We claim the ornamental design for a bowling table with ball rack and storage shelves, as shown and described.

DESCRIPTION

FIG. 1 is a front perspective view of the bowling table with ball rack and storage shelves in accordance with an embodiment of the present invention;

FIG. 2 is a right side perspective view thereof;

FIG. 3 is a left side perspective view thereof;

FIG. 4 is a top plan view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a bottom plan view thereof; and,

FIG. 10 is a bottom perspective view thereof.

The bottom portion of each leg of the bowling table and the bowling balls shown the ball racks of each of the above-referenced figures are for illustrative purposes only and form no part of the claimed design.
